UNITED STATES PATENT OFFICE.

GODFREY M. S. TAIT, OF WASHINGTON, DISTRICT OF COLUMBIA, ASSIGNOR TO HARRY M. MARBLE, OF NEWARK, NEW JERSEY.

TAR-EXTRACTOR.

1,262,571.

Specification of Letters Patent. Patented Apr. 9, 1918.

Application filed March 24, 1911, Serial No. 616,685. Renewed August 11, 1917. Serial No. 185,796.

To all whom it may concern:

Be it known that I, GODFREY M. S. TAIT, of Washington, D. C., have invented certain new and useful Improvements in Tar-Extractors, of which the following is a full, clear, and exact specification, such as will enable others skilled in the art to which it appertains to make and use the same.

My invention relates to an apparatus for extracting tar and similar impurities from producer gas, and to the combination of such an apparatus with means for transmitting the gas to the engine or to another point of utilization for controlling the pressures of the gases thus transmitted. According to this I employ a peculiar form of centrifugal fan which in addition to violently throwing the solid matter outward from the path of movement of the gas acts to impel the gas itself through the pipe line to the engine and combines a pressure regulating means permitting the gas to be by-passed back to the suction side when an excess pressure is developed in the pipe line to the engine.

My invention also involves a novel means of subjecting the gas to the action of moisture, whereby to emulsify the tar and volatile constituent of the gas and render its separation in the extractor easy and thorough.

The invention involves various other features of importance, particularly those relating to the relative construction and arrangement of the impeller blades and housing, all of which will be fully set forth hereinafter and particularly pointed out in the claims.

Reference is now had to the accompanying drawings, which represent, as an example, the preferred embodiment of my invention.

In these drawings—

Figure 1 is a vertical section of the invention;

Fig. 2 is a side view of one of the larger impeller wheels;

Fig. 3 is a section thereof;

Fig. 4 is a side view of one of the smallest impeller wheels;

Fig. 5 is a section of the same;

Fig. 6 is a detail section showing a slight modification in the form;

Fig. 7 is a sectional view of a further modification.

The apparatus as shown in Fig. 1 is provided with a base 10, in which a water pan 11 is formed in any suitable manner. 12 in-

dicates a foundation plate on the base and on this is fastened the foundation or base flange 14 of the main casting or body of the tar separator. Said main casting or body 60 of the tar-separator has two pedestals 15 with bearings 16 carrying the axle shaft 17 of the impeller wheels so that the same may be rotated rapidly by power applied to the shaft in any desired manner. 65

The body of the tar extractor is also provided with an inlet chamber 18 at one side and an outlet chamber 19 at the other to the inlet chamber 18 and a gas supply pipe 20 extends in which a steam spray nozzle 21 70 discharges toward the inlet chamber 18 acting on the gas as will fully appear herein-after. Between the inlet and outlet chambers 18 and 19 three separator chambers 22, 22^a and 22^b are arranged. These are circular 75 in form and are of gradual increasing diameter. The smallest chamber 22 communicates with the chamber 18 through a gateway 23, while the largest chamber 22^b discharges into the outlet chamber 19 through 80 a larger opening or passageway 24. The three separator chambers 22, 22^a and 22^b have at their discharge or outlet sides inwardly projecting annular walls 25, which extend from the outer walls of the chambers slightly inward and mark the divisions 85 between the chambers. From the bottoms of the separator chambers passageways 26, 26^a and 26^b extend downward through the body of the separator where they meet corresponding openings in the base plate 12 and communicate with tubes 27, 27^a and 27^b extending downward into a body of water 90 maintained at a predetermined level in the pan 11 by an overflow pipe 28. A pipe 29 95 extends from the bottom of the outlet chamber 19 downward into said water so that its lower end is sealed by the same. The inlet chamber 18 communicates at its bottom with said water pan 11 through an opening 30, 100 which, however, is not water-sealed, as will be seen by reference to Fig. 1.

In each of the separator chambers an impeller wheel is located. Each impeller comprises a hub 31 to which a web 32 is fastened. 105 This web 32 carries radial blades 33. The webs 32 extend outward in proximity with the inner edges of the walls 25 of their respective separator chamber leaving, however, annular spaces between the peripheries 110 of the webs and the said walls for the movement of the gas. The impeller which is lo-

cated within the chamber 22 has its blades 33 extending the whole length of the web, while the other two impellers have their blades extending from the peripheries of the webs and inward past the walls 25 but not to the hubs. This distinction is by reason of the different diameters of the impeller wheels, the larger wheels not requiring the ribs along their whole faces. The said 5 blades or ribs 33 are located at the inlet side of the webs so that in rotating they bring about a centrifugal motion of the materials within the separator and induce a pressure through the same toward the outlet chamber, 10 as will fully appear hereinafter. The shaft 17 is hollow and connected with a water supply and is perforated as at 34, the perforations matching with the perforations in the hub 31 so that the water may flow from 15 the pipe into the separator chambers as will also fully appear hereinafter.

The operation of the apparatus is as follows:

Upon rotation of the shaft 17 and the attached impeller wheels the blades 33, located 20 on the inlet sides only of said wheels, serve to throw outward the fluid contents of the tar extractor body and draft or impel the same from one chamber to another of said 25 body. This induces a suction in the inlet connection 18 and a corresponding pressure in the discharge connection 19 which draws the gas and its volatile content into the extractor body where it is taken up by the impeller wheels and thrown violently outward 30 as it successively passes through the chambers in which the wheels are located. Simultaneously water is supplied through the hollow shaft 17, which passes outward along 35 the impeller wheels and takes up the tar and volatile content of the gas and thrown with the same outward beyond the peripheries of the wheels. The tar thus separated falls to the bottoms of the separator chambers and 40 escapes into the pan 11 through the connections 27, 27^a and 27^b or to any other point to which it may be desired to lead the discharge. The gas, however, under the influence of the impeller wheels, is caused to 45 move progressively from one separator chamber to the other and out into the discharge connection 19.

This, it will be seen, not only draws the gas through the separator, but maintains a 50 certain pressure in the discharge line, causing the gas to flow to the point of consumption. Should the consumption of the gas fall below normal and an excess pressure be thereby generated in the discharge line this 55 will, acting in the connection 29, break the water seal and flowing therethrough into the pan 11 and from thence back to the suction or inlet side through the opening 30. This 60 it will be seen by-passes the gas to the suction side and automatically maintains the

pressure in the discharge side at a predetermined point. In regard to this feature of the apparatus it is pointed out that the tar discharge tubes 27, 27^a and 27^b need not necessarily pass into the pan 11 and in fact it 70 is preferable for them to pass into the separate chamber or receptacle, since the pan or receptacle 11 should be closed from atmospheric communication to prevent escape of the gas and to insure its return into the inlet connection 18.

During the operation of this apparatus, and in order that the tar vapor may be thoroughly emulsified before coming in contact with the rotaries, I introduce into the gas 80 line at some point, a steam jet, 21, supplying steam, preferably of a high temperature. The object of introducing steam at this point is for the emulsification of the volatile matter in the gas which, if brought in 85 contact with finely divided moisture forms a fairly stable emulsion. It follows therefore that by using steam instead of water at this point that the steam being more highly divided than water forms the best type of 90 spray and makes a proportionately higher emulsion, with the result that the moisture in the steam condenses on the tiny globules of volatile matter adding weight thereto, so that when same reaches the tar separator 95 the centrifugal action of same has a greater weight to act on, and therefore acts with very much greater rapidity and precision, thereby facilitating the mechanical operation of the apparatus.

Fig. 6 shows a modification of the invention in which the webs of the impeller wheels are formed with opening, 35, closed by gates, 36, which slide in guideways, 37. These gates are normally opened by springs, 38, and are held so while the impeller wheels are stationary. But when rotation begins the gates move outward to closed position by centrifugal force overcoming the action of the springs. This arrangement allows 100 the gas to flow freely through the separator when the separator is not in operation and under certain conditions this may be at times desirable.

Fig. 7 shows a further modification in 115 which the open spaces inside of the impelling blades, 33, are filled by a conical shield or drum, 39. This includes the hollow shaft 17 and the water is led from said shaft to the inner ends of the impelling blades by 120 means of tube, 40. This drum covers and incloses the otherwise dead space in the tar separator and prevents a partial vacuum which might otherwise form at this point from disturbing the above-described operation of the tar separator.

The speed in revolutions of the impeller wheels may be controlled by the governor, 50, preferably of the usual ball-type and connected to the engine. The usual sliding 130

collar, 51, is actuated through a bell crank lever, 52, which may be connected by a rod, 53, to a movable lever, 54, preferably pivotally mounted on the frame, 15. This lever 5 carries a hand operated pawl, 54^a, which is adapted to move over a toothed quadrant, 55. This lever is attached to the shaft, 17, whereby the wheels, 32, may be changed with relation to the inclosing walls 25 and 10 their discharge force accordingly regulated.

Having thus described my invention what I claim as new and desire to secure by Letters Patent of the United States is:

1. The combination of a tar extractor body 15 with annular baffle walls therein, arranged to form a horizontal series of communicating extractor chambers, of successively increasing diameter and rotating extractor wheels arranged in said chambers and also of successively increasing diameter, and mounted 20 to rotate about a substantially horizontal axis, the extractor wheels having blades thereon to impel the gas from one chamber to the other, and the said extractor chambers having tar outlets in their lower portions.

2. The combination of a tar extractor body with annular baffle walls therein arranged to form a horizontal series of communicating 30 extractor chambers, of successively increasing diameter and rotating extractor wheels arranged in said chambers and also of successively increasing diameter, and mounted to rotate about a substantially horizontal axis, the extractor wheels having blades thereon to impel the gas from one chamber to the other, said blades being arranged on the receiving side only of the impeller wheels, and the said extractor chambers having tar outlets in their lower portions.

3. The combination of a tar extractor body with annular baffle walls therein arranged to form communicating extractor chambers, of successively increasing diameter and rotating extractor wheels arranged in said chambers and also of successively increasing diameter, the extractor wheels having blades thereon to impel the gas from one chamber to the other, the peripheries of the impeller 50 wheels being arranged in proximity to the inner edges of the respective baffle walls, the diameter of each impeller wheel being less than the internal diameter of the corresponding baffle wall, whereby space is provided between the periphery of each impeller wheel and the inner periphery of each baffle wall for the flow of gas to the next succeeding chamber.

4. The combination of a tar extractor body 60 with annular baffle walls therein arranged to form communicating extractor chambers, of successively increasing diameter, rotating extractor wheels arranged in said chambers and also of successively increasing 65 diameter, the extractor wheels having blades

thereon to impel the gas from one chamber to the other, and an automatically controlled by-pass means from the discharge to the receiving side of the tar extractor.

5. The combination of a tar extractor body 70 with annular baffle walls therein, arranged to form communicating extractor chambers, of successively increasing diameter, rotating extractor wheels arranged in said chambers and also of successively increasing 75 diameter, the extractor wheels having blades thereon to impel the gas from one chamber to the other, and a water-sealed by-pass means from the discharge to the receiving side of the tar extractor. 80

6. A tar extractor having an extractor body with a plurality of horizontally arranged extractor chambers communicating with each other and successively increasing in diameter and means for impelling the 85 contents of the said body outward in the chambers and from the smaller to the larger successively, the axis of said extractor body and of the extractor chambers therein being substantially horizontal, said chambers having in their lower portions outlets for the discharge of separated tar. 90

7. A tar extractor having an extractor body with a plurality of horizontally arranged extractor chambers communicating 95 with each other and successively increasing in diameter and means for impelling the contents of the said body outward in the chambers and from the smaller to the larger successively, comprising rotating impellers 100 in the chambers, the axis of said extractor body and of the extractor chambers therein, and the axis of rotation of said impellers, being substantially horizontal, said extractor chambers having in their lower portions outlets for the discharge of separated tar. 105

8. A tar extractor having an extractor body with a plurality of extractor chambers communicating with each other and successively increasing in diameter, means for impelling the contents of the said body outward in the chambers and from the smaller to the larger successively, and a closed drum 110 attached to the extractor wheels inward of the blades, the drum also increasing in diameter from the receiving to the discharge side of the tar extractor.

9. The combination of a pressure developing tar extractor, a pipe line conducting the gas from the tar extractor to the point of 115 gas consumption and a by-pass for returning excess pressure in the pipe line to the suction side of the tar extractor, the by-pass provided with a seal to prevent the flow of gas therethrough in but one direction. 120

10. The combination of a pressure creating tar extractor, a water container below the tar extractor and having direct communication with the inlet connection of the 130

4
tar extractor, a pipe line receiving the gas from the tar extractor and conducting it to the point of gas consumption and means constituting a passage from the interior of the tar extractor to the water container, such passage being normally sealed by the water therein.

11. The combination of a tar extractor body with annular baffle walls forming extractor chambers and inlet and outlet connections respectively at the sides of said chambers, a rotary shaft extending through the baffle walls, centrifugal fan wheels in said extractor chambers and mounted on the shaft, means for carrying off the tar and water comprising outlet devices from the bottom of each extractor chamber and outlet passage from the inlet connection of the extractor body and means for by-passing excess pressure from the discharge to the receiving side of the extractor.

12. A tar extractor having means forming extractor chambers communicating with each other and centrifugal fan wheels operating in said chambers, the webs of said wheels having openings therein provided with gates to close the openings upon the development of centrifugal force and yielding means for opening the gates upon the cessation of such force.

13. A tar extractor having a body, a plurality of partitions forming separate extractor chambers communicating with each other, inlet and outlet connections respectively at the side of said chambers, a water chamber below said body and having passages leading from the chambers therein to points beneath the water level in said water chamber and an open communication between said body and the upper portion of the water chamber.

14. A tar extractor having an extractor chamber, a centrifugal fan wheel, an opening therein, a water chamber beneath the extractor chamber and a conduit leading from the lower portion of said extractor chamber to a point below the water level in the water chamber, the extractor having open communication between the inlet of said extractor chamber and the upper portion of said water chamber, whereby gas escaping from said extractor chamber through the said conduit may return to the inlet of the extractor chamber.

15. A tar extractor having an extractor chamber, a centrifugal fan wheel, an opening therein, a water chamber beneath the extractor chamber and conduit leading from the lower portion of said extractor chamber to a point below the water level in the water chamber, the extractor having open communication between the inlet of said extractor chamber and the upper portion of said

water chamber, whereby gas escaping from said extractor chamber through the said conduit may return to the inlet of the extractor chamber, and means for by-passing the gas from the discharge side of the tar extractor into the water chamber and thence to the inlet side.

16. A tar extractor having an extractor chamber, a centrifugal fan wheel, an opening therein, a water chamber beneath the extractor chamber and a conduit leading from the lower portion of said extractor chamber to a point below the water level in the water chamber, the extractor having open communication between the inlet of said extractor chamber and the upper portion of said water chamber, whereby gas escaping from said extractor chamber through the said conduit may return to the inlet of the extractor chamber, and means for by-passing the gas from the discharge side of the tar extractor into the water chamber and thence to the inlet side, said means including a water seal preventing back flow of gas in the by-pass.

17. The combination of a tar extractor body with annular baffle walls therein, arranged to form a horizontal series of communicating extractor chambers, of successively increasing diameter and rotating extractor wheels arranged in said chambers and also of successively increasing diameter, said extractor wheels arranged to rotate about an approximately horizontal axis, the said extractor chambers having in their lower portions outlets for the discharge of separated tar, the extractor wheels having blades thereon to impel the gas from one chamber to the other, and means for introducing an emulsifying agent into the gas.

18. The combination of a tar extractor body with annular baffle walls therein, arranged to form a horizontal series of communicating extractor chambers, of successively increasing diameter and rotating extractor wheels arranged in said chambers and also of successively increasing diameter, said extractor wheels arranged to rotate about an approximately horizontal axis, the said extractor chambers having in their lower portions outlets for the discharge of separated tar, the extractor wheels having blades thereon to impel the gas from one chamber to the other and a steam jet in intimate contact with the gas whereby the volatile matter in the gas is emulsified.

In testimony whereof I have signed my name to this specification in the presence of two subscribing witnesses.

GODFREY M. S. TAIT.
